UNITED STATES PATENT OFFICE.

WILLIAM MORRIS BOWER, CHARLES SAMBROOK BURDON, AND CARL LOUIS STERN, OF LONDON, ENGLAND, ASSIGNORS TO LINOTYPE AND MACHINERY LIMITED, OF LONDON, ENGLAND, A BRITISH COMPANY.

METHOD AND MOLD FOR CASTING TYPE BARS.

Application filed October 20, 1924, Serial No. 744,566, and in Great Britain October 22, 1923.

This invention relates to the molds of typographical line casting machines for producing the larger sizes of slugs such as carry display faces or characters and for economy 5 of metal, are of hollow or cellular formation.

Heretofore difficulty has been experienced in producing these slugs with satisfactory printing faces, and of sufficient rigidity to withstand the great pressure to which they 10 are exposed when used in a printing press or for making stereotype matrices from dry flongs.

The defective printing faces are believed to be largely attributable to the molten metal 15 in the molds becoming chilled before all parts of the matrix cavities are flooded with such metal, and, so far as regards the absence of rigidity, this is due to the fact that the feet of the slugs or the upright members 20 or walls of said slugs do not furnish a support which is adequate to prevent distortion under the above mentioned pressure.

According to the present invention the aforesaid difficulty is entirely overcome by 25 causing the molten metal to be injected into the mold through two sets of jets extending continuously throughout the length of the mold cavity so that the introduction of the metal takes place in the shortest possible 30 time.

In the accompanying drawings the invention is illustrated in connection with a mold of the general construction employed in machines known commercially under the trade 35 mark "Linotype",

Figure 1 being a front elevation of the mold with the present improvements applied thereto;

Figure 2 an end elevation of the mold;

Figure 3 a plan of the improved core, and

Figures 4 and 5 respectively an elevation and sectional view of the slug produced according to the invention.

The mold comprises, as ordinarily, a mold body 1, and a mold cap 2 held to the body by screws 3, the cap and body being separated so as to form the mold slot 4, by a pair of liners 5.

In order to form the cells in the slug body, according to the present invention, a core 6 is provided in the mold slot 4. This core 6 is supported on each liner 5, beneath a filling piece 7 which completes the closure

of the space between the liner 5 and the 55 mold cap 2, and is secured in place by the screws 3 passing through holes 8 in the core.

As shown particularly in Figure 3, the core 6 has notches 9 in the edge which is presented towards the front of the mold. It 60 is to be noted that the width "w" of the core 6 is less than the corresponding fore-and-aft dimension of the mold slot 4, and that the core is supported by the liners 5 in such a position that the last-mentioned edge is located to the rear of the front of the mold slot, while the opposite or rear edge is flush with the rear edge of that slot. The rear portion of the mold slot 4 is thus divided into upper and lower sections for forming 70 the upright members or walls 10 (Figure 5) of the slug, while the front portion of the mold slot remains clear for the formation of the character-bearing shelf 11.

When casting the improved slug according 75 to the present invention the front of the mold slot is closed, as ordinarily, by the composed line of matrices, and metal is injected into both the upper and lower sections at the rear of the mold cavity thus formed, 80 through two jets, or two series of jets, extending along the whole length of that cavity, so that the introduction of the metal takes place in the shortest possible time.

By these means the metal reaches the 85 matrix cavities uniformly throughout the length of the mold, and equally at the top and bottom of the mold cavity, with the result that the metal in said matrix cavities also cools off uniformly, producing on solidification a smooth and unblemished printing surface 12. Moreover, as the feet of the two longitudinal upright walls 10 of the slug body are both in the same plane 90 throughout their entire length and extend 95 from foot to shoulder, these walls 10 form a rigid support for the printing face throughout its entire length so that the latter cannot be distorted by any pressure which it may be subjected to in the printing press or in 100 the process of stereotype production. The slug is further strengthened by the intermediate transverse walls 13 formed by the notches 9 of the core 6.

It will be recognized that liners 5 and filling pieces 7 of different dimensions may be employed in conjunction with the core 6, and be interchanged to enable slugs of 105

correspondingly different lengths or body dimensions to be cast.

Having described our invention, we declare that what we claim and desire to secure by Letters Patent is:—

1. The method of casting slugs or type bars of hollow formation, which consists in providing a cored mold presenting two sections in which the side walls of the slugs are cast, and injecting molten metal into both of said sections simultaneously.

2. The method of casting slugs or type bars of hollow formation, which consists in providing a cored mold presenting two sections in which the side walls of the slugs are cast, and injecting molten metal into both of said sections simultaneously in sep-

arate streams extending throughout the length of the sections.

3. A cored slug-casting mold comprising a mold body, a mold cap, sectional end liners separating the body and cap to form the mold cavity and a core suspended between the liners and dividing the mold cavity into two sections in which the side walls of the slug are cast, said liners being separate from the core and freely interchangeable independently of the core to vary the dimensions of the mold cavity.

In testimony whereof we have affixed our signatures hereto.

WILLIAM MORRIS BOWER.

CHARLES SAMBROOK BURDON.

CARL LOUIS STERN.
